US0D1087509S

(12) **United States Design Patent** (10) **Patent No.:** **US D1,087,509 S**
(45) **Date of Patent:** **** Aug. 5, 2025**

(54) **HANDHELD VACUUM CLEANER ASSEMBLY**

(71) Applicant: **BSH Hausgeräte GmbH**, Munich (DE)

(72) Inventors: **Thomas Eric Beliveau**, Munich (DE);
Daniel Dockner, Munich (DE); **Tobias Neutz**, Munich (DE); **Jan Wertel**, Berlin (DE); **Gernot Oberfell**, Munich (DE); **Dirk Licht**, Munich (DE)

(**) Term: **15 Years**

(21) Appl. No.: **35/521,852**

(22) Filed: **Apr. 23, 2024**

(80) **Hague Agreement Data**

Int. Filing Date: **Apr. 23, 2024**

Int. Reg. No.: **DM/238693**

Int. Reg. Date: **Apr. 23, 2024**

Int. Reg. Pub. Date: **Aug. 2, 2024**

(51) **LOC (15) Cl.** **15-05**

(52) **U.S. Cl.**

USPC **D32/18**

(58) **Field of Classification Search**

(57) **CLAIM**

The ornamental design for a handheld vacuum cleaner assembly as shown and described.

DESCRIPTION

1. Handheld vacuum cleaner assembly

1.1 : Perspective

1.2 : Handheld vacuum cleaner assembly (Out of Operation)

1.3 : Handheld vacuum cleaner assembly (In Operation)

1.4 : Left

1.5 : Back

1.6 : Top

1.7 : Bottom

1. Title of the product incorporating the design: Handheld vacuum cleaner assembly. 2. Use of the product incorporating the design : Use as handheld vacuum cleaner assembly.

3. Essential features of the design: As shown by the shapes of Design 1.4. Photograph designated to best show the essential features of the design: Perspective view of Design

1.5. Basic Design: Design 1.

1 Claim, 7 Drawing Sheets
